UNITED STATES PATENT OFFICE.

HENRY F. STARRETT, OF CHICAGO, ILLINOIS, ASSIGNEE TO STARRETT MANUFACTURING COMPANY, OF CHICAGO, ILLINOIS, A CORPORATION OF ILLINOIS.

PANEL-BOARD AND PANEL-BOARD CONSTRUCTION.

1,325,052.

Specification of Letters Patent. Patented Dec. 16, 1919.

Application filed May 15, 1918. Serial No. 284,589.

To all whom it may concern:

Be it known that I, HENRY F. STARRETT, a citizen of the United States, residing at Chicago, in the county of Cook and State of Illinois, have invented new and useful Improvements in Panel-Boards and Panel-Board Construction, of which the following is a full, clear, concise, and exact description, reference being had to the accompanying drawing, forming a part of this specification.

My invention relates to improvements in panel-boards and panel-board constructions, and, more particularly, to a panel-board unit provided with an improved means for covering or inclosing the wire gutter.

In the specific embodiment of my invention herein illustrated and described, I have preferred to show a form of panel-board more especially adapted to be used in the wiring of houses or residences, but obviously is also useful and can be readily incorporated or used in any and all panel-board structures in which a wire gutter is utilized.

As is well known to those skilled in the art, according to underwriters' requirements in all panel-board structures in which more than four circuits are wired, the branch circuits must be brought in opposite the branch line terminals, or as an alternative, if this is not desirable, a concealed wire gutter must be provided. This wire gutter is usually constructed by building a frame around the outer edge of the panel-board base which carries the circuit-controlling equipment. This frame may be made either of insulating material or metal, in which latter case the holes perforated in this frame through which the circuit wires are carried must be insulated by suitable bushings or fitted with eyelets, so as to present a smooth surface to prevent injury to the insulation of the conductors. Due to this extra wire gutter construction, panel-boards equipped with such a wire gutter are more expensive than the panel-board units in which the branch circuit wires are brought in opposite the fuse terminals.

One of the objects of my invention is to improve the construction of panel-board units provided with wire gutters, whereby the cost of such panel-board units may be materially reduced. Another object resides in the production of an improved covering for the wiring gutter, said cover serving,

first, to obscure from view the wires in the wire gutter; second, to constitute a suitable barrier through which the wires may be fed to the circuit-controlling apparatus mounted on the panel-board; and, third, as an insulating medium for the current-carrying conductors or bus-bars located on the base of the panel-board. Other objects and advantages of my invention will become apparent from the following description and will be more specifically pointed out in the appended claims.

In the drawings, in which one embodiment of my invention is shown—

Figure 1 is a front elevation showing a panel-box and meter and the conduits leading to the panel-box, the cover of the box being broken away to show the inclosed panel;

Fig. 2 is a section on the line 2—2 of Fig. 1 through the panel and panel-box;

Fig. 3 is a fragmentary enlarged sectional view on the line 2—2 of Fig. 1 illustrating the main line fuse construction;

Fig. 4 is a fragmentary enlarged sectional view on the line 2—2 of Fig. 1 illustrating the branch circuit panel and fuse construction;

Fig. 5 is a sectional view on the line 5—5 of Fig. 1;

Fig. 6 is a bottom plan view of the outer plate of the panel-board showing the bus-bars; and

Fig. 7 is a perspective view showing a portion of the panel-board and the panel-box and the wiring connections.

Referring now to the drawings in detail, the construction shown comprises a flush panel-box 10 which is set flush in the wall or building construction 11, a panel-board 11' mounted and inclosed in the panel-box 10, a meter 12 associated with the panel-board 11', and conduits 13 leading to the panel-box 10 and in which are located the conductors for the branch circuits, and conduits 14 also leading to the panel-box and in which are located the main conductors leading to the panel-board. The specific panel-board shown is of the two-wire fused main-switch type but my invention may obviously be adapted to any and all types of panel-board constructions.

The panel-board 11' comprises an insulating base upon which are mounted the main fuse receptacles 15, the main switch 17, the 119

branch fuse receptacles 18, the main connection terminals 19, and the branch connection terminals 20 and a bus-bar system 21. The insulating base is made in three parts. These parts are the front plate 22 which supports the main fuses 16 and the main switch 17, the front plate 23 which supports the branch fuse receptacles 18 and their terminals, and the rear plate 24 which 10 extends beneath both of the front plates and between which and the front plates the bus-bar system 21 is inclosed and housed. These plates may be of any suitable insulating material, such as a molded insulating composition.

The insulating rear plate 24 is supported in the panel-box 10 by means of a pair of brackets 25 secured to the bottom of the panel-box in any suitable manner, as by 20 screws 26. The plates 22 and 23 are secured to the rear plate 24 in any suitable manner, as by means of screws 27. The screws 27 located at the ends of the rear plates 24 extend through these rear plates and are 25 screwed into the brackets 25 to secure the panel-board to the brackets. The brackets 25 space the panel-board a sufficient distance from the bottom of the panel-box to provide 30 a wiring space between the panel-board and the bottom of the box for the wiring connections for the main and branch circuits and the meter.

The rear plate 24 is provided with a plurality of notches or recesses 28 in its edges, 35 which afford passage for the wiring connections from the wiring space between the panel-board and the bottom of the box to the binding-terminals 19 and 20 for the main and branch circuits, respectively, and 40 to the binding-terminals 29 for the meter connections. The side edges 30 of the front plates 22 and 23 are located a sufficient distance from the sides of the panel-box to permit the passage of the wiring connections 45 between said edges and the sides of the box, as shown in Figs. 5 and 7.

Positioned over the terminal connections 29 is an insulating housing 29^a, which completely covers the meter connections and prevents tampering therewith. This housing is 50 cut out to fit over the terminal connections and so that the base thereof will rest upon the surface of the panel-board. The housing is secured to the panel-board by means of 55 two bolts 29^b. The bolts 29^b are secured in the panel-board in any suitable manner and protrude upwardly from the front face thereof so as to project through the upper face of the housing. The extreme forward 60 end of these bolts are transversely perforated.

When the housing 29^a is put into place it is securely held in this position by the nuts 29^c which are screwed down on the bolts 29^b 65 to the surface of the housing. When these

nuts have thus been put in place, a wire 29^e is inserted through the transverse perforation in the bolt, and this wire is permanently sealed by a sealing means such as 29^f. It consequently follows that when the meter 70 has been wired into the panel-board and the housing 29^a secured in position and sealed, it will be impossible to tamper with the meter connections without such acts being detected.

The panel-board may be reinforced by a 75 pair of steel strips 30' (Figs. 2 and 5) which extend across the joint between the front plates 22 and 23 into which the screws 27 extend.

Each main fuse receptacle 16 comprises an 80 insulating base 31 and shell and center contacts 32 and 33, respectively, for engagement with the corresponding contacts of the fuse-plug. The center contact 33 comprises a screw extending through an opening in the 85 conductor strip 34, which extends from the binding-terminal 19, the screw being threaded into a nut 35 located in a recess in the rear face of the plate 22 (Figs. 2 and 3). The shell contact 32 is electrically connected 90 with the switch contact 36 by means of a conducting plate 37, to one end of which the switch-contact 36 is secured and the other end of which is in engagement with the flange 38 of the shell contact 32. The shell contact 32 is held in place on the base 31, and the base 31 is held in place on the plate 22 by means of the screw center contact 33, the head of which bears on a metal washer 39, which washer in turn bears on an insulating 95 washer 40, which bears on the end of the strip 37, which is in engagement with the flange 38 of the shell contact 32.

The switch 17 comprises a pair of pivot-posts 41 of conducting material, a pair of 100 contact-blades 42, one pivoted to each of the posts 41, a cross-piece 43 of insulating material connecting the arms 42; and a handle 44 connected to the cross-piece 43 for actuating the switch. The pivot-posts 41 are electrically connected with two of the binding-terminals 29, respectively, for the meter 12. The pivoted arms 42 are so mounted as to make or break connection with respect to the 110 switch contacts 36.

The branch circuit fuse-receptacles 18 are made in pairs. Each pair, as shown in Fig. 4, comprises an insulating base 45, two center contacts 46, and two shell contacts 47 supported by the insulating base 45. One of 120 the center contacts 46 is electrically connected with a bus-bar of one polarity, and the other contact 46 of the fuse-receptacle 18 is electrically connected with a bus-bar of the opposite polarity.

Referring to Fig. 6, which shows the bus-bar arrangement, the bus-bar 48 is shown riveted at 49 to a terminal 50, which extends through the plate 23 from one of the binding-terminals 29 of the meter. Two aux- 130

iliary bus-bars 51, extending transversely, are secured to the main bus-bar 48 by means of rivets 52. One center contact of each of two of the branch-circuit fuse-receptacles 18 is screwed into the auxiliary bus-bars 51 and one center contact of each of two of the branch circuit fuse receptacles 18 is screwed into the bus-bar 48.

The bus-bar 53, of opposite polarity to that of the bus-bar 48, is secured by means of rivets 54 to a terminal 55, which extends through an opening in the front plate 23 and is electrically connected with one of the binding-terminals for the meter. Two transversely-extending auxiliary bus-bars 56 are secured to this same bus-bar 53 by means of rivets 57. One center contact of each of two of the fuse-receptacles 18 is screwed into these transversely-extending bus-bars 56 and one center contact of each of two of fuse-receptacles 18 is screwed into the bus-bar 53 as indicated at 46 in Fig. 6. The bus-bars 48, 51, 53 and 56 are located in recesses in the insulating plate 23. The auxiliary bus-bars 56 are insulated from the main bus-bar 48 by means of rectangular sheets 57 of insulating material placed between the bus-bar 48 and the auxiliary bus-bars 56. A similar sheet of insulating material 57' is placed between the main bus-bar 53 and the auxiliary bus-bars 51 which it crosses.

Each shell contact 47 is electrically connected with one of the binding terminals 20 of the branch circuit connections by means of a conducting strap 58 having an annular portion into which are threaded screws 59, the heads of which engage the flange 60 of shell contact 47.

In assembling a panel-box unit of the type described, the bus-bars and circuit controlling apparatus are first secured to the front plate 22, after which the bus-bars are placed in position in the recesses provided therefor in the front plate 23. The front plates 22 and 23 are then secured to the rear plate 24 by means of the screws 27, as hereinbefore described.

After the plates have been thus assembled, the circuit-controlling apparatus, that is, the fuse receptacles, are mounted in position on the front plate 23 and the panel-board is then in position to be mounted on the brackets provided therefor in the panel-box.

In installing a panel-box of this type, the panel-board is withdrawn from the box and the main, branch, and meter conductors connected to their respective terminals, sufficient slack being left in these conductors so that the panel-board can be readily withdrawn from the box so as to permit inspection of the wires thereunder.

When the wires have been thus connected they are fitted in the notches 28 in the rear plate 24 provided therefor, and the panel-

board is then slipped back into position in the box and secured to the mounting brackets 25 by means of the screws 27.

It will be evident from the foregoing description that the rear plate 24 functions to cover and insulate the current-carrying conductors or bus-bars at the rear of the front plates 22 and 23, and also serves to hold the bus-bars on the front plate 23 in position, and that it further serves as a covering for the wiring gutter formed around the panel-board proper, the notches in said rear plate 24 serving as guiding and positioning means for the conductors or wires which are brought up from underneath the panel to be connected to terminals of the circuit-controlling apparatus mounted on the front of the board.

According to my invention, therefore, a very simple and cheap construction is provided for panel-board units equipped with a covered or inclosed wire gutter.

Obviously, my invention is not limited to the specific embodiment thereof herein illustrated and described, but is capable of many variations and applications within its spirit and scope as set forth in the following claims.

What I claim as new and desire to secure as Letters Patent is:—

1. In a device of the character described, in combination, a panel-box, a panel-board comprising a plurality of front plates and a rear plate, circuit-controlling apparatus mounted on said front plates, the said rear plate being of greater width than said front plates, whereby a protruding ledge of said rear plate extends from the side edges of said front plates, the width of said rear plate being substantially equal to the inner width of said panel-box, means to secure said front plate to said rear plate, and means for mounting said panel-board in said panel-box.

2. In a device of the character described, in combination, a panel-box, a panel-board comprising a plurality of front plates and a rear plate, circuit-controlling apparatus mounted on said front plates, said rear plate being greater in width than said front plate, whereby a ledge protrudes from the side edges of said front plates, the width of said rear plate being substantially equal to the width of said panel-box, means to secure said front plate to said rear plates, means to mount said panel-board in said panel-box, and means associated with said rear plate to permit the passage of wires therethrough, said wires connecting with the apparatus mounted on said front plate.

3. In a device of the character described, in combination, a panel-box, a panel-board consisting of a front plate and a rear plate, said rear plate being of greater width than said front plate so as to form a protruding

- ledge on each side of said front plate, said rear plate fitting snugly in said panel-box, means for attaching said front plate to said gear plate, means for mounting said panel-board in said panel-box, whereby a wiring space is provided below said panel-board, and means associated with said rear plate to permit the passage of said wires from beneath said panel-board to the front thereof.
4. In a device of the character described, in combination, a panel-box, a panel-board consisting of a front plate and a rear plate, grooves cut in the rear surface of said front plate, bus-bars fitted in said groove, means to secure said rear-plate to said front plate to maintain said bus-bars in position in said grooves, said rear plate being of a greater width than said front plate, so as to form a protruding ledge on each side of said front plate, said rear plate fitting snugly in said panel-box, means for mounting said panel-board in said panel-box, whereby a wiring space is provided below said panel-board, and means associated with said rear-plate to permit the passage of said wires from beneath said panel-board to the front thereof.
5. In a device of the character described, in combination, a panel-box, a panel-board consisting of a plurality of front plates and a rear plate, each of said front plates carrying circuit-controlling apparatus of different character, means to secure said front plate to said rear plate, said rear plate being of greater width than said front plate so as to form a protruding ledge on each side of said front plate, said rear plate fitting snugly in said panel-box, means for mounting said panel-board in said panel-box whereby a wiring space is provided below said panel-board, and means associated with said rear plate to permit the passage of wires from beneath said panel-board to the front thereof, said wires passing over the edges of said front plate, said rear plate serving to obscure the wiring of said panel-board located beneath said panel.
6. A panel-board and panel-box construction comprising, in combination, a panel-box, a panel-board mounted therein and spaced apart from the bottom of said box, conduit openings in said box, a wiring gutter formed around said panel-board, said panel-board comprising a front plate and a rear plate, said rear plate fitting snugly in said panel-box and being of greater width than said front plate, whereby a protruding ledge is formed on each side of said front plate to cover said wire gutter.
7. A panel-board and panel-box construction comprising, in combination, a panel-
- box, a panel-board mounted therein and spaced apart from the bottom of said box, conduit openings in said box, a wiring gutter formed around said panel-board, said panel-board comprising a front plate and a rear plate, said rear plate fitting snugly in said panel-box and being of greater width than said front plate, whereby a protruding ledge is formed on each side of said front plate to cover said wiring gutter, and means associated with said rear plate to permit the passage of wires from beneath said panel-board to the front thereof.
8. A panel-board and panel-box construction comprising, in combination, a panel-box, a panel-board mounted therein and spaced apart from the bottom of said box, conduit openings in said box, a wiring gutter formed around said panel-board, said panel-board comprising a front plate and a rear plate, circuit-controlling apparatus mounted on said front plate, said rear plate fitting snugly in said panel-box and being of greater width than said front plate, whereby a protruding ledge is formed on each side of said front plate to cover said wiring gutter, and notches cut in said rear plate along the line of union between the exterior edges of said front plate and said rear plate to permit the passage of wires through said rear plate over the side edges of said front plate for connection to the apparatus mounted on the said front plate.
9. In a panel-board and panel-box construction, in combination, a panel-box, a panel-board, said board comprising an apparatus-mounting front plate and a panel-box inclosing rear plate, fastening means for interconnecting said front and rear plates, a protruding ledge of said rear plate extending from the side edges of said front plate, and a wiring gutter, said protruding ledge inclosing said wiring gutter.
10. In a panel-board and panel-box construction, in combination, a panel-box, a panel-board, said board comprising an apparatus-mounting front plate and a panel-box inclosing rear plate, fastening means for interconnecting said front and rear plates, a protruding ledge of said rear plate extending from the side edges of said front plate, a wiring gutter, said protruding ledge covering said wiring gutter, and notches cut in said protruding ledges to permit the passage of wires from said wiring gutter through said rear plate and to the apparatus mounted on said front plate.

In witness whereof, I have hereunto subscribed my name.

HENRY F. STARRETT.
